TRANSFORMER FOR OPEN AND CLOSED SIGNAL SYSTEMS

Filed Oct. 21, 1926

UNITED STATES PATENT OFFICE.

WILLIAM F. LEATHER, OF CHICAGO, ILLINOIS.

TRANSFORMER FOR OPEN AND CLOSED SIGNAL SYSTEMS.

Application filed October 21, 1926. Serial No. 143,077.

My invention relates to transformers, and in its general objects, my invention aims to provide an inexpensive and easily constructed transformer which can be used interchangeably on normally open circuits, normally closed circuits, or on combinations of normally open and normally closed circuits, and which can be operated on a closed circuit for long periods of time with no perceptible heating.

More particularly, my invention provides a transformer adapted to be connected to an ordinary alternating current lighting circuit (such as the commonly used 110 volt circuit) for furnishing current intermittently at low voltages to an electric bell or an audible signal, and for also supplying current continuously to a burglar alarm circuit, toy train or the like.

In one of its immediate commercial applications, the transformer of my invention is particularly suited for use in a burglar alarm system in which an interruption of a normally closed circuit actuates a switch so as to close the normally open circuit to a bell or other electrically operated signal device. Hence I am illustrating and describing my transformer as employed for such a purpose, though I do not wish to be limited to any particular use of my invention.

In the drawings;

Fig. 1 is a perspective view of a combined open circuit and closed circuit transformer embodying my invention.

Fig. 2 is a side elevation of the two transformer cores, also showing the dielectric which is desirably interposed between the main core and the auxiliary core.

Fig. 3 is an elevation of one of the major parts of the laminated main core.

Fig. 4 is an elevation of one of the supplemental strip parts of the main core.

Fig. 5 is an elevation of one of the laminations of the auxiliary end core.

Fig. 6 is a diagram showing the connections of the transformer windings in a burglar alarm system in which a trip is operated by the interruption of a normally closed circuit, and in which the actuation of this trip closes a normally open bell circuit.

Fig. 7 is a somewhat diagrammatic horizontal section through my transformer as employed in the system of Fig. 6, showing how the several windings are respectively

connected to the source of current supply, the relay or trip device, and the signal bell.

Referring first to the diagram of Fig. 6, this includes a transformer in which the main inductance winding 1, fed from a 110 volt supply circuit, is in inductive relation to a secondary winding 2 and also to an auxiliary winding 3. The secondary winding 2 is in series with a circuit which includes both an electric bell 4 and a normally open switch, the switch being shown as including a stationary contact 5 and a pivoted switch arm 6, which switch arm is normally held above and out of engagement with the contact 5 by a detent arm 7 carried by a pivoted armature 8, so that the bell circuit is normally open.

The auxiliary winding 3 is in series with an interrupter 9, which may be of any type commonly employed in closed circuit burglar alarm systems, so as to afford a normally closed circuit. This interrupter is shunted by a circuit 10 through an electromagnet 11 which is disposed for lifting the armature 8 when current flows through the electromagnet, but the winding of the latter is of such resistance that no appreciable current flows through it unless the interrupter 9 is actuated. When the normally closed circuit through the interrupter 9 is ruptured, the current induced in the transformer winding 3 flows through the shunt circuit 10 and causes the electromagnet 11 to raise the armature 8, thereby releasing the detent 7 and permitting the switch arm 6 to close the circuit to the bell 4, so that the bell will ring continuously until the switch arm is manually returned to its detent-latched position.

In operating such an alarm system, it is necessary to have both an available supply of current for the electric bell (or other equivalent alarm signal) and a supply of current for the closed circuit through the burglar-actuated interrupter. The voltages suitable for these two currents may vary according to the size of the bell (or other alarm device) and according to the lengths of the respective circuits. Moreover, it is important that the continuous flow of current through the circuit leading to the interrupter 9 (or to a plurality of such rupturable elements arranged in series after the manner customary in closed circuit burglar

alarm systems) will not cause any considerable heating of the transformer.

To meet these conditions and to obtain current for all parts of the system from a single unit, I construct my transformer with two cores disposed so that the main core affords a closed magnetic circuit through both the supply (or main) winding and the secondary (bell circuit) winding which is normally open, while the auxiliary core cooperates with the main core in affording a partly open magnetic circuit disposed in effective relation to the auxiliary (or detent-actuating) winding and designed for radiating any generated heat.

For this purpose, Figs. 1 to 4 show the main transformer core as built of laminations each of which comprises a major part shaped like a letter E turned on one side, and a supplemental part in the form of a strip disposed in edgewise engagement with the ends of the three parallel arm portions of the said letter E. These laminations are alternately turned with the back of the E at the bottom and at the top, as shown at 13 in Figs. 2 and 3, and with the supplemental strips 14 alternately at the top and the bottom of the core, and the assembled laminations are secured to each other by bolts 15. Thus assembled, the main core is of a form sometimes employed in shell type transformers.

For the auxiliary core, I employ laminations 16 each punched like a letter E, with the arms desirably of a length equal to the total height of the main core portion. However, these laminations 16 may be smaller in each of their other dimensions as less space is needed between their arms for portions of windings, and the total thickness of the auxiliary core portion may be considerably less than that of the main core portion. These laminations 16 desirably all have their arms extend in the same direction, as shown in Fig. 1, and are suitably secured to each other, as for example by rivets 17.

This auxiliary core is disposed at right angles to the main core, with its central stem 13^a extending parallel to one lateral stem of the main core but spaced from the latter stem by a dielectric 18. Thus assembled, the two cores are employed in connection with an inner primary winding 1, a secondary winding 2 surrounding the winding 1, and a third winding 3 which is superposed at one side on the secondary winding 2 and which passes around the outer face of the medial stem of the auxiliary core. Thus arranged, the main core and the windings 1 and 2 constitute a shell type transformer, and the winding 3 is an additional winding which I have found highly suitable for use on a closed circuit. To allow for this third winding without materially reducing the efficiency of the shell type trans-

former portion, I make the space A between the medial shank of the main core and the side shank 13^b adjacent to the auxiliary core just wide enough to receive the superposed primary and secondary windings 1 and 2. Then I make the space B between the medial shank and the other shank 13^c of the main core sufficiently wider than the space A to accommodate the third winding 3 also.

In manufacturing such a transformer, the two inner windings, namely the supply current or main winding 1 and the open circuit winding 2 can readily be wound on a suitable spool or mandrel and secured to each other to form a hollow unit. Likewise, the closed circuit coil 3 can be preformed and slipped over the said hollow unit, and the entire auxiliary core can be assembled as a separate unit. Then the main core can be assembled by slipping its consecutive lamination portions into place respectively from opposite ends of the said hollow unit, and bolting the parts of the assembled core together, after which the auxiliary core has its medial arm slid between one end of the main core and the part of the coil 3 which extends around that core end.

With the transformer thus arranged, it will be obvious from Figs. 1 and 7 that the secondary (or bell-circuit) winding is disposed in the same well closed magnetic circuit with the main winding 1 and in close inductive relation to the latter, thereby making my transformer quite efficient for giving a loud alarm signal.

At the same time, the winding 3, which is in series with the electromagnet of the detent-releasing device, has a considerable portion in inductive relation to the same main transformer winding 1 and has another portion in inductive relation to the medial shank 16^a of the auxiliary core. This shank 16^a is closer to the winding 3 than the adjacent shank 13^b of the main core and the shank 16^a partly shields the winding 3 from the inductive action of variations in flux through the shank 13^b, as will be seen from Fig. 7, so that the winding 3 is more largely influenced by the central shank 16^a of the auxiliary core than by the end shank 13^b of the main core. The current in the winding 3 flows in the same direction around the exterior of the shanks 13^a and 16^a, hence the predominating inductive influence of the shank 16^a over the shank 13^b augments that of the shanks 13^a and 13^c on the winding 3. For example, if the magnetizing influence of the current in the main winding 1 during one half cycle of the alternations makes the top of the medial shank 13^a of the main core portion a south pole, as marked in Fig. 2, the tops of the lateral shanks of this main core portions would be north poles. The auxiliary core portion has its medial shank parallel to one of the said lateral shanks of

the main core portion, but spaced from it by a dielectric 18. Hence the magnetizing of the last named main core shank will induce an opposite magnetization in the medial shank of 5 the auxiliary core portion, thus making the upper end of the latter shank a south pole and making the upper ends of the end shanks of the auxiliary core portion north poles, as marked in Fig. 5. Since the winding 3 passes in the same direction around 10 the medial shanks of both core portions and since these both have their south poles simultaneously either at the upper or the lower ends, the variations in magnetic flux 15 through these two medial shanks act conjointly on the winding 3. So also, since a part of this winding passes inside the lateral shanks of the auxiliary core, or effectively in a reverse direction from that 20 around the medial shank of this core, the magnetic fluctuations in these lateral shanks also induce a current flow in the same direction in the winding 3.

Consequently, I can secure an adequate 25 efficiency for the generation of the continuously closed alarm circuit while keeping the major portions of the cores employed in that connection (namely, the left-hand shank 13, and the two lateral shanks 30 16^A and 16^B in Fig. 1) freely exposed to the cooling effect of the outer air. Furthermore, I permit air to circulate around considerable portions of the third winding. Hence, I have found in practice that my 35 transformer remains substantially cool even when the burglar alarm circuit is operated continuously for months, whereas a similar shell type core with all three windings disposed within it in the older manner would 40 heat to such an extent as to melt various insulating materials.

In practice, I have found it advantageous 45 to dispose the secondary winding 2 between the third winding 3 and the primary winding 1. However, I do not wish to be limited to this feature, nor to the details of the construction and assemblage above described, as many changes might obviously be made 50 without departing either from the spirit of my invention or from the appended claims.

Neither do I wish to be limited to the employment of my invention in a transformer arranged for supplying current to a normally open as well as another and normally 55 closed circuit, since my arrangement of the cores and of the windings 1 and 3 would obviously operate also if the winding 2 were omitted. So also, the current generated in the secondary winding 2 may be employed 60 for other purposes in addition to the operation of an alarm controlled by current through the winding 3. For example, taps 65 12 might be run from the circuit of the winding 2, as indicated in dotted lines in Fig. 6, for operating ordinary house bell circuits,

thus making my transformer furnish currents for the regular door bells in addition to the burglar alarm circuit.

I claim as my invention:

1. In a transformer, a main core having 70 three parallel shanks; an auxiliary core also having three parallel shanks, and having its medial shank spaced from, but in magnetizable relation to, one lateral shank of the main core; and coil windings including a 75 main winding extending around the medial shank of the main core inside the lateral shanks of the main core, and a second winding extending around the medial shank of the auxiliary core and between that shank 80 and the lateral shanks of the auxiliary core, the second winding also having a portion extending around the medial shank of the main core between the latter shank and the other lateral shank of that core. 85

2. A transformer as per claim 1, in which the said portion of the second winding is disposed between the said other lateral shank of the main core and the main winding.

3. A transformer as per claim 1, in which 90 the coil windings also include a secondary winding surrounding the main winding and extending inside the lateral shanks of the main core.

4. A transformer as per claim 1, in which 95 the coil windings also include a secondary winding surrounding the main winding and having a part disposed between the main winding and the said portion of the second winding. 100

5. A transformer for supplying current from a supply circuit both to a normally closed circuit and to a normally open circuit, comprising a main core having three parallel shanks, an auxiliary core having a shank 105 parallel to and spaced from one lateral shank of the main core; a supply circuit winding surrounding the medial shank of the main core, a normally open circuit winding surrounding the supply circuit winding, the said two windings both extending 110 between the medial and the lateral shanks of the main core; and a normally closed circuit winding having one portion extending between the said open circuit winding and the 115 other lateral shank of the core, and having another portion extending outside the first named lateral shank and around the outer face of the said shank of the auxiliary core.

6. In a voltage reducing transformer, a 120 core including three parallel shanks, a main winding and a secondary winding both extending around the medial shank of the core, and between the medial shank and both lateral shanks of the core; a third winding 125 extending around the main winding between the latter and one lateral shank of the core and extending outside the other lateral shank of the core, and an auxiliary core having a part thereof disposed outside and 130

spaced from the said other lateral shank and inside the third winding.

7. A transformer as per claim 6, in which the auxiliary core also has other portions in inductive relation to the third winding and disposed outside the latter.

8. In a transformer, a main core of hollow rectangular vertical section having an added central stem nearer to one side of the core than to the other side; an auxiliary core disposed at right angles to the main core, the vertical section of the auxiliary core in a plane at right angles to the aforesaid vertical section being a U with an added central shank, the said shank being adjacent to the said first named side of the main core; a dielectric spacing the said shank from the said first named side of the main core; a pair of windings both extending around the central stem of the main core and passing be-

tween the said stem and both sides of the main core; and a third winding extending between the said stem and the said other side of the main core, and extending outside the said shank of the auxiliary core.

25

9. The combination with a transformer core including a pair of parallel shanks, of a primary winding and a secondary winding both extending between the two shanks around the first of the said shanks, an auxiliary core including an auxiliary core shank disposed parallel to but spaced from the second of the aforesaid two shanks, and a third winding extending around the oppositely directed faces of the said first shank and the said auxiliary core shank.
